UNITED STATES PATENT OFFICE

2,605,138

ANTIOFFSET APPARATUS

Jens A. Paasche, Wilmette, Ill.

Application August 18, 1949, Serial No. 110,956

1 Claim. (Cl. 299—86)

1 In the stacking, or otherwise superimposing, of printed sheets, one of the problems has been to prevent the "offset" of the freshly-applied ink from one sheet to the next superimposed surface. For years it has been the practice to prevent this "offsetting" by treating the printed sheet, as it leaves the press or after it has come to rest on a stacking platform, with a substance so finely atomized as to form a coating over the ink so as to provide a spacing of the sheets sufficient to prevent contact of the wet ink with the face of a subsequently-superimposed sheet, which substance has a tendency to improve the appearance of the printed sheet.

In certain cases a fluid has been used for this coating; in other cases a powder has been used. For each, certain advantages are asserted. However, for certain types of printing, the simultaneous atomization of fluid and powder will achieve results superior to those obtained by the use of fluid or powder separately.

The main objects of this invention, therefore, are to provide an improved apparatus for use in separately or simultaneously spraying atomized fluid and powder on freshly-printed sheets to prevent "offset" of ink from one sheet to the next superimposed thereon; to provide an apparatus of this kind having an improved supporting means which will permit an atomizing fluid-assembly or an atomizing powder-assembly to be mounted thereon for individual use or permit both assemblies to be mounted thereon for simultaneous use; to provide an improved supporting means of this kind which may be attached to a printing press frame or to a portable standard positionable at the side of the press; and to provide improved means connecting a press-actuated valve-controlled source of air pressure to the fluid- and the powder-assemblies when they are individually mounted on said supporting means or to both assemblies when they are both mounted on said supporting means for separate or simultaneous use.

In the accompanying drawings:

Fig. 1 is a perspective view of the combined fluid- and powder-assemblies adapted for separate or simultaneous spraying of fluid and powder on printed sheets;

Fig. 2 is a view of the upper portion of the supporting standard showing the mounting of the fluid-assembly employing a dual airbrush arrangement; and

Fig. 3 is a similar view showing the mounting of the powder-assembly.

A "no-offset" fluid and powder spray apparatus

2 constructed in accordance with this invention comprises, a complete fluid-assembly 5 and a complete powder-assembly 6 for which a supporting standard 7 is provided to mount either or both of the assemblies for individual or simultaneous use under the control of a press-operated timing mechanism 8.

The fluid-assembly 5 comprises an arm 9 on which is mounted one or more airbrushes 10 connected to a fluid container 11 by a hose 12 and to a source of air pressure which is under the control of a press-actuated timing mechanism 8 and which is maintained between a certain minimum and maximum pressure by the regulators 13 and 14.

The arm 9 is in the form of a conduit or tube. It is telescopically supported on a sleeve 15, forming a part of the standard 7, so as to position the airbrushes cantilever-fashion over printed sheets 20 discharged from a press. A cam clamp 16 mounted on the sleeve 15 serves to lock the arm 9 in proper position.

The airbrushes 10, two of which are mounted on the arm 9 (Fig. 2), are of a construction shown 25 and described in Patent No. 2,401,503, issued June 4, 1946. They are adjustable so as to accommodate the pattern and size of the spray to the needs for each printing situation.

The regulator 13 is in the nature of a check 30 valve, the construction and operation of which is fully shown and explained in copending application Serial No. 110,955, filed August 18, 1949 now Patent No. 2,595,600 issued May 6, 1952. It serves to maintain a constant minimum pressure 35 in the conduit arm 9 instantly available at the airbrushes 10 when the timing mechanism 8 cuts in the air pressure for a spraying action.

The pressure regulator 14 is of a type similar 40 to that shown in Patent No. 2,398,503, issued April 16, 1946, but conforming in structure with that shown in the aforesaid copending application Serial No. 110,955. The regulator serves to limit the maximum pressure to which air in the line can rise during the operation of the airbrushes 10.

The powder-assembly 6, the form and construction of which are more fully set forth in the aforesaid copending application, comprises an arm 9' on one end of which is mounted a powder atomizing head 10', and on the other end of which is a fitting 17 which mounts a valve-controlled powder supply 18. The powder supply is connected to a source of air pressure under the control of the press-actuated timing mechanism 8 and the air pressure regulators 13' and 14'.

The arm 9' is a conduit or tube the same as the arm 9 for the fluid-assembly. It is adapted to be telescopically supported in the sleeve 15 so as to effect a cantilever positioning of the atomizing head 10' over printed sheets as they are discharged from a printing press.

The powder atomizing head 10' may be of either slotted form or perforated form. The former is preferable for use when the spraying of powder is to be effected during the travel of the printed sheet from the press. The latter is preferred when the spraying is to be effected after the sheet has left the press and come to rest on a stacking platform.

The valve-controlled powder supply 18, which is subject matter of the aforesaid copending application, provides a regulated amount of powder to the atomizing head 10' as determined by the operation of the timing mechanism 8.

The air regulators 13' and 14' are of a form and function identical with the regulators 13 and 14 for the fluid assembly.

The standard 7 comprises a pipe or tube 19 telescopically supported in a sleeve 20 mounted on a portable base 21 whereby one or the other or both of the fluid- and powder-assemblies may be properly positioned with respect to the printing press and the printed sheets discharged therefrom.

The pipe or tube 19 is provided with a transverse opening 22 into which the sleeve 15 is welded. This pipe or tube 19 also contains an air conditioner adapted to extract from the air any moisture, oil, or other foreign particles that might interfere with the proper functioning of the several parts which effect the atomization of the fluid or powder by the airbrush 10 or the atomizing head 10'. At its upper end the tube 19 is closed by a cap 23 which is so formed as to support the fluid container 11.

The sleeve 20 is provided with a cam clamp 24 whereby the assembly-supporting sleeve 14 may be properly positioned above the sheets being sprayed.

As herein shown, the base 21 for the sleeve 20 is a portable unit wherein is arranged a motor-driven compressor for supplying the desired air pressure for operating the fluid- and powder-assemblies 5 and 6. Where it is desired to mount the standard 7 directly onto the printing press, a suitable bracket could be substituted for the portable base 21 and could be bolted to the printing press frame at a point which would properly position either or both of the spray assemblies with respect to the printed sheets being discharged from the press.

The timing mechanism 8 comprises a valve mechanism 25 mounted on a bracket 26 whereby it is suitably attached to the press frame. The valve mechanism 25 is connected by tubes or hoses 27 and 28 with the air conditioner in the tube 19 and the air regulator 14 or 14'. The air conditioner is obviously connected to a source of air pressure. A cam 29 of appropriate form is mounted on an operating part of the press so as to intermittently trip a pin 30 for actuating the valve 25 to effect the desired spraying of the printed sheets.

The assemblies 5 and 6 may be mounted individually on the standard 7 for separate use, or they may be mounted conjointly on the standard 7 for either separate or simultaneous use.

When these assemblies are mounted for in-

dividual use, the conduit arm 9 or 9', as the case may be, is inserted in the sleeve 15 and clamped in position. When it is desired to have both of these assemblies mounted on the standard, so as to be instantly available for either separate or simultaneous use, the conduit arm for the assembly 5 is generally inserted in the sleeve 15 and the conduit arm 9' for the powder-assembly 6 is inserted in the sleeve 15', which sleeve 15' is clamped to the sleeve 15 of the fluid-assembly 5 by clamps 31 and 32. The arms 9 and 9' are adjusted in their respective sleeves 15 and 15' so as to position the airbrush 10 and the powder atomizing head 10' in the desired relationship to each other and to the printed sheets discharged from the printing press.

In the fluid- and powder-assembly combination, such as is shown in Fig. 1, the tube or hose 28 from the valve mechanism 25 is provided with branches 33 and 34 leading to the conduit 9 and the fitting 17 on the conduit 9' through the medium of the respective air regulators 14 and 14'. Manually-shiftable valves 35 and 36 (see Fig. 1) are arranged in the branches 33 and 34 so that the air from the source of pressure, as controlled by the valve mechanism 25, may be admitted selectively to the respective assemblies 5 and 6, or simultaneously, depending upon the set of said valves.

Although but one specific embodiment of this invention has been herein shown and described, it will be understood that details of the construction shown may be altered or omitted without departing from the spirit of the invention as defined by the following claim.

I claim:

An offset-preventing unit comprising a portable base for housing a source of compressed air, an upright sleeve mounted on said base, a vertically adjustable pipe supported in said sleeve, an air conditioner in said pipe, a liquid reservoir supported on the upper end of said pipe, a rigid horizontally disposed tube supported on said pipe, a valve-controlled air line communicating with said air conditioner and with said tube, an air brush mounted on said tube and communicating with said air line through said tube, a conduit for conducting liquid by gravity from said reservoir to said air brush, a powder spray assembly including a rigid, horizontally extending conduit, means for detachably securing said conduit to said tube, a powder atomizing head at one end of said conduit, a powder supply disposed at the other end of said conduit; and means for connecting said valve controlled air line to said other end of said conduit and said powder supply, said air brush and said air atomizing nozzle being in coacting relation whereby powder and liquid can be simultaneously applied to a printed sheet to prevent offset.

JENS A. PAASCHE.
